UNITED STATES PATENT OFFICE.

AARON TERRY, OF SPRINGFIELD, MASSACHUSETTS.

NEW MEANS AND SYSTEM OF HEATING.

1,305,755.

Specification of Letters Patent. Patented June 3, 1919.

Application filed February 14, 1918. Serial No. 217,160.

To all whom it may concern:

Be it known that I, AARON TERRY, a citizen of the United States of America, residing in Springfield, in the county of Hampden and State of Massachusetts, have invented New Means and Systems of Heating, of which the following is a specification, reference being had to the accompanying drawings and letters of reference marked 10 thereon.

It is a well known fact that the heating systems now in use are not economical and that many experts claim that from 75 to 90 per cent. of the heat units are wasted and 15 that as a general rule not exceeding 5 per cent. of the heat units are actually utilized for heating purposes.

In the systems now in use a large percentage of the heat units are lost because of the 20 fact that the heat is largely taken up in heating the conduits and heavy radiators and because of the fact that the heated gases escape through the chimney without first giving up the heat carried by them.

25 The objects of my invention are to provide a means whereby a very much larger percentage of the heat units may be utilized for heating purposes than has heretofore been attained, and a means or system 30 wherein the waste heretofore had is largely avoided.

I accomplish the objects of my invention by the construction herein shown.

In the accompanying drawings illustrating 35 one embodiment of my invention and in which like characters of reference indicate like parts,

Figure 1 is a perspective view of a furnace shell.

40 Fig. 2 is a view of a radiation basket-like structure.

Fig. 3 is a perspective view of a preferred form of conduit.

Fig. 4 is a vertical sectional view of a 45 heating drum.

Fig. 5 is a perspective view of two heating drums arranged to operate together or independently.

Fig. 6 is an elevation in section of a furnace shell showing two heating drums mounted therein.

Fig. 7 is a like view showing means for the employment of coal, coke or other fuel as a heating medium.

Fig. 8 is a detached view of a section of the heating drum.

One of the great problems in heating a dwelling or other building is the difficulty of utilizing the heat actually generated by the heating means and of conducting the 60 heat units to the desired point.

For illustration in a steam heating plant it becomes necessary to heat the water in the boiler, which must result in heating the boiler itself and all appliances connected therewith, thus wasting a large amount of the heat units at the outset. The whole circulating system must then be heated in order to conduct the steam at a sufficiently high temperature to the room to be heated. 70 It then becomes necessary to supply sufficient heat to heat a radiator, thus again taking up the heat units before they reach a point where the room begins to receive the benefit of the heating system. It is a well 75 known fact that a large volume of the heat units are carried away in smoke and other products of combustion so that but a comparatively small percentage of the heat generated by the heating means is in fact utilized for heating purposes.

In order to overcome this condition and provide a means whereby the heat actually generated at the source may be readily absorbed, given off and conducted to the desired point, I avoid the use of heavy, thick material and provide a construction wherein the heat units may be rapidly gathered and carried to the point desired before the temperature is materially reduced.

The first step to accomplish the result to be attained comprises the employment of one or more heating drums each constructed by preference, as at present advised, as shown in Figs. 4, 5, 6 and 7. This drum 85 comprises an outer shell 1, formed of thin material, preferably sheet copper or brass and by preference having its surface corrugated. Within the outer shell I arrange an inner shell 2 of like construction and arrange the same substantially as shown in Figs. 4, 6 and 7. The bottom of the shell 1 is open, while the bottom of the shell 2 is closed. Both shells are open at the top. Between the outer and inner shells of the 100 heating drum I prefer to arrange a basket-like structure similar to that shown in Fig. 2.

Referring now to Fig. 4, heat is applied to the lower open ended portion 4 and it will be readily seen that the heated air will pass upwardly between the shells 1 and 2 5 and become rapidly absorbed by these shells, and as the shells have large corrugated radiating surfaces, with their corrugations arranged to baffle the heated air so that in its passage upward between said shells it 10 will be deflected back and forth from one to the other, they will generate intense heat and give it off in great volume. If, now, an arrangement be made so that the air currents will flow up between these two 15 shells, the air will become heated and if the air so heated be quickly conducted through proper conduits to the rooms or places to be heated, a very much larger percentage of the heat units will be utilized 20 for heating purposes than has heretofore been found possible.

The employment of a heat radiating member, such as the basket-like structure 3 shown in Fig. 2, arranged between the outer 25 and inner shells of the drum serves to break up and further heat the air currents and bring all particles in contact with a heated surface, thus insuring the thorough heating of all the air passing between the shells 30 of the drum.

In Fig. 4 I show a construction wherein the heat absorbed by the inner shell will be permitted to flow upwardly and because of the employment of a dish shaped deflecting plate 5 will be deflected downwardly and be again thrown in contact with the heating drum, and will then pass upwardly in its outward travel in substantially close contact with the upper portion of the inner 40 shell and thus be further heated and conducted to the desired point, so that in the construction shown in Fig. 4 the heat units absorbed by the air in contact with both the inner and outer shell may be utilized.

In Fig. 6 I illustrate two drums opening at the top into a conduit 22, and an arrangement whereby air is allowed to enter the inner and bottom portions of the inner shells 2 through an approximately vertical conduit 6 having horizontal branches 23 which turn downwardly and open above the closed bottoms of said inner shells. The air thus introduced into the inner shells 2 is projected or descends onto the bottoms of 55 said shells, and then rises in contact with the sides of said shells, and to this end the outlet terminals of the branches 23 are surrounded with annular deflectors 33. The intake of the conduit 6 must be below the 60 level of the open bottoms of the shells 1, in an inclosure to which particular reference will subsequently be made, with the discharge ends of said conduit or of its branches 23 just above the closed bottoms of the shells

2, as previously observed. Thus the passage 65 of air into the shells 2 is insured, and the air is discharged at the points where it is subjected to the most intense heat.

Suitable dampers 7 and 8 are provided for the heating drums in the conduit 22 for 70 regulating the flow of air from the heating drums, and for cutting off either of such drums.

The drums in this view, Fig. 6, are heated by means of gas-burners 51 on a T 52 at 75 the inner end of a pipe 53 which receives its supply from an outside pipe 54.

In order to facilitate the flow of the heated air I prefer to arrange a fan 9 in the conduit 22 preferably driven by an electric motor 10, which fan will operate to force the air upwardly to the desired point.

In Fig. 6 I show an arrangement of water tanks 11 designed to moisten the heated air on its passage.

In Fig. 7 I illustrate a construction wherein coal coke or other like fuel may be conveniently employed and with this arrangement I prefer to employ a reservoir 12 arranged at an elevation above the fire box 13 90 with a conduit 14 extending between the two and I provide a fan 15, driven by a motor 16, the fan being arranged in a conduit 17 extending to the ash box 18, by the employment of which fan a forced draft may be 95 had and a more complete combustion attained. In this figure I also illustrate the employment of a hot air fan 9, driven by a motor 10. The conduits 19 and 20 lead to a chimney and thus dispose of the products 100 of combustion, but as the smoke and other heated products of combustion pass upwardly between the corrugated outer and inner shells of the drums the heat units will be absorbed so that the smoke and gases 105 will pass out through the chimney, after having given off substantially all of the heat units carried by them. The heat units given off by the outer surface of the outer shell 1 of the drum will pass upwardly and through the conduits 21 connected with the cupola of the furnace and are mixed with the heat units which pass upwardly from the interior of the drum, the latter being forced 110 upwardly by the fan as before described. 115 Air, as before described, is admitted to the interior of the drum-like structure immediately above the closed bottom of the shell 2 through a conduit 6^a, the intake of which is below the level of the open bottom 120 of the shell 1, all as in the other case.

By way of illustration I show in Fig. 8 one form of corrugated structure which I consider desirable to be employed in the manufacture of the drum, although I do not limit myself to any particular form of corrugation or irregular surface.

It will readily be seen that any heating

means may be employed to heat the drum, it simply being necessary to provide means which will furnish heat to the lower open end portion of the outer shell 1 of the drum, 5 or in other words to provide means for furnishing heated air to pass upwardly between the outer and inner shells and, as before stated, it is also desirable to provide means in many instances for the flow of air to the 10 interior portion of the inner shell of the drum so that the heat units to be given off by the shells may be utilized for heating purposes. It will therefore readily be seen that the employment of gas, kerosene, electricity or other means for heating may be employed with my device.

Electricity might be employed as a heating means, and one way in which it could be applied would be through the medium of a 20 resistance coil or similar element located at the base of the drum or drums.

I do not limit myself to any particular means for furnishing heat and applying the same to the drum or drums.

25 It will also be seen that the arrangement of conduits, dampers, fans and deflecting devices may also be arranged and constructed differing in detail and location from that shown by me without departing 30 from the spirit of my invention, and I therefore do not limit myself to the construction shown, but refer to the same as one embodiment of my invention.

The cupola in which the conduits 21 are 35 located is mounted at the top of an inclosing structure 25 having at the top deflector members 24 which direct the heat waves from the drum or drums below to said cupola. This structure or inclosure is made 40 with the end in view of conducting the heat generated by the inclosed drum or drums to the conduits 21 with as little loss as possible. The aforesaid drum or drums are supported within the inclosure 25, in the present instance, by being suspended from a light cross bar 30 having its ends seated in brackets 31 on opposite sides of said inclosure.

50 The purpose of the inclosure 25 is to conserve the heat radiated from the outer shell or shells 1 and thus to insure the utilization of practically all of the heat generated by the drum or drums for heating the rooms to which it is conveyed by way of the conduits 21. The construction of the apparatus as a 55 whole is such that little or no heat is given off from the inclosure 25 into the space surrounding the same, but is conveyed away through the top of said inclosure.

60 The office of the fan 9 is threefold:—First, the action of the fan draws the air into the shell or shells 2 through the conduit 6 or 6^a; second, said action sucks the air out of the top of said shell or shells, and out of the top of the shells 1 in the Fig. 6 construction;

and third, said action forces the air upwardly toward the conduits 21. This is an important and valuable feature of the invention.

Air from the outside is supplied to the inclosing structure 25 through a conduit 50, 70 Figs. 1, 6, and 7, which opens into the back side of said structure.

The air supplied to the interior of the shell or shells 2, in either example herein shown, being of the temperature of the air 75 in the inclosure 25, from which it is taken, is in consequence more uniform or even in temperature and much better adapted for the purpose for which it is used than would be the case if the same were taken from the 80 outside. And the uniformity or evenness is enhanced by reason of the fact that the air is taken from below the heating point or points, thus being cool without being cold, and comparatively fresh and lively, as is 85 needed for the supply to the shell or shells 2.

Having therefore described my invention what I claim as new and desire to secure by Letters Patent is:—

1. The combination, in a heating appliance, with an inclosure provided with a heat conduit, of a heating drum supported in said inclosure and comprising inner and outer shells both open at the top, the inner shell closed at the bottom, and the outer shell 95 open at the bottom, means to introduce air from a point in said inclosure which is below the level of the open bottom of said outer shell into the interior of said inner shell onto the bottom thereof, said means being 100 provided at its discharge end with a deflector member, and means to apply heat to said drum at the bottom.

2. The combination, in a heating appliance, with an inclosure provided with a heat 105 conduit, of a heating drum supported in said inclosure and comprising inner and outer shells both open at the top, the inner shell closed at the bottom, and the outer shell 110 open at the bottom, means to introduce air from a point in said inclosure which is below the level of the open bottom of said outer shell into the interior of said inner shell onto the bottom thereof, said means being 115 provided at its discharge end with a deflector, a downwardly concave deflector in said inner shell above said first-named deflector, means to apply heat to said drum at the bottom, and means to suck the heated air from the top of said drum.

3. In a heating appliance, an inclosure, a 120 ranged to throw the air currents back and outer cone-shaped shells having imperforate corrugated walls with the corrugations arranged to throw the air currents back and 125 forth from one wall to the other, within said inclosure, said shells being open at the top and said inner shell being closed at the

- bottom, an air conduit entering said inner shell, from a point below the open bottom of said outer shell, and opening downwardly onto the bottom of said inner shell, a deflector on the discharge end of said conduit, a deflector in said inner shell over said first-named deflector, and means to apply heat to said shells at the bottom.
4. In a heating appliance, an inclosure, a heat conduit leading therefrom, inner and outer cone shaped shells having imperforate corrugated walls with the corrugations arranged to throw the air currents back and forth from one wall to the other, said shells being open at the top, said inner shell being closed at the bottom, and said outer shell being open at the bottom, an air conduit entering said inner shell and opening downwardly onto the bottom thereof, and means to apply heat to said shells at the bottom.
5. The combination, in a heating appliance, with an inclosure, and a heat conduit leading therefrom, of a plurality of drums and a conduit common to said drums, in said inclosure, each of said drums comprising inner and outer shells opening at the top into said second-named conduit, the inner shell being closed at the bottom, and the outer shell being open at the bottom, and said second-named conduit opening into said inclosure, a conduit opening at the bottom into said inclosure and extending into said inner shells and opening therein, and means to apply heat to said drums at the bottom.
6. The combination, in a heating appliance, with an inclosure, and a heat conduit leading therefrom, of a plurality of drums and a conduit common to said drums, in said inclosure, each of said drums comprising inner and outer shells opening at the top into said second-named conduit, the inner shell being closed at the bottom, and the outer shell being open at the bottom, onto the bottom of said inner shell, a deflector on the discharge end of said conduit, a deflector in said inner shell over said first-named deflector, and means to apply heat to said shells at the bottom.
7. The combination, in a heating appliance, with an inclosure, and a heat conduit leading therefrom, of a plurality of drums and a conduit common to said drums, each of said drums comprising inner and outer shells opening at the top into said second-named conduit, the inner shell being closed at the bottom, and the outer shell being open at the bottom, and said second-named conduit opening into said inclosure, means to suspend said drums with said second-named conduit in said inclosure above the floor thereof, a conduit opening at the bottom into said inclosure and extending into said inner shells, and means to apply heat to said drums at the bottom.
8. In a heating appliance, a conduit having an opening in the top thereof, drums connected with said conduit, each of said drums comprising inner and outer shells opening at the top into one end of said conduit, the inner shell being closed at the bottom, and the outer shell being open at the bottom, and a conduit opening into said inner shell and having an intermediate part that opens outside of said drums, substantially as shown.

AARON TERRY.

Correction in Letters Patent No. 1,305,755.

It is hereby certified that in Letters Patent No. 1,305,755, granted June 3, 1919, upon the application of Aaron Terry, of Springfield, Massachusetts, for an improvement in "New Means and Systems of Heating," an error appears in the printed specification requiring correction as follows: Page 3, claim 3, strike out line 122 and insert the words *heat conduit leading therefrom, inner and;* and that the said Letters Patent should be read with this correction therein that the same may conform to the record of the case in the Patent Office.

Signed and sealed this 15th day of July, A. D., 1919.

[SEAL.]

R. F. WHITEHEAD,

Acting Commissioner of Patents.

Cl. 126—106.
